[57] CLAIM

The ornamental design for an adjustable wall mounting fixture, as shown and described.

DESCRIPTION

FIG. 1 is a front elevational view of an adjustable wall mounted lighting fixture shown my new design; FIG. 2 is a rear elevational view thereof;

FIG. 3 is a fragmentary left side elevational view thereof;

FIG. 4 is a fragmentary right side elevational view thereof;

FIG. 5 is a fragmentary top plan view thereof;

FIG. 6 is a fragmentary bottom plan view thereof; and, FIG. 7 is a top, front, right side perspective view thereof on a reduced scale.

The support arm is broken away in FIGS. 3, 4, 5, and 6 for convenience of illustration.
